SPECIAL PURPOSE COMPUTER FOR DETERMINING CUT LENGTH OF ELONGATED MATERIAL

Jury Stepanovich Pavlenko, Izzaslav Vasiljevich Vasiljev, Victor Grigorjevich Pribysh, Iosif Vladimirovich Sigalov, Petr Timofeevich Starostin, Nicolai Andronnikovich Tantsjura, Ilna Abramovna Fridman, and Victor Evgenijevs Khodosko, all of Kiev, U.S.S.R., assignors to Kievsky Gosudarstvenny Universitet J.G. Shevchenko
Filed Dec. 30, 1963, Ser. No. 338,553
10 3 Claims. (Cl. 235—157)

This invention relates to computing machines or rather to devices used to find the most favorable variant for dividing a roll of fabric of arbitrary length into cuts of prearranged lengths, which would leave a minimum remnant, when figuring fabrics in needlework factories before laying out the material for cutting.

The efficient utilization of fabrics in needlework factories engaged in mass production of wearing apparel has great economic significance. By reducing the amount of irrational remnants, which cannot be used for turning out articles, the additional amount of useful articles produced by the industry becomes increased.

The cutting of fabric for mass sewing is done as follows: A roll of fabric is cut up into strips, the length of which is sufficient for making one or several articles. Scores of such strips of equal length are subsequently placed into a strip bed one on top of the other and the required articles are cut out simultaneously.

A roll of fabric may be cut into strips of equal length only if the length of the strip is a multiple of the length of the entire roll. However, due to the fact that the length of a fabric roll may be of any size reaching up to a 100 and more meters, while the length of a strip required for a certain article is invariable and runs in the range of 1 to 12 meters, cases of multiplicity are comparatively rare.

For the purpose of reducing the amount of remnants, estimation is made on the basis of the length of cutting beds for all articles made from the same kind of fabric. If one of the strip lengths is not a multiple of the length of the fabric roll, combinations are made up of two or three strips. Combinations of four strips are seldom practiced in factories for reasons of organizational difficulties.

Combinations are selected with a view of obtaining the least possible remnants. When one or several combinations leave a similar amount of remnants, preference is given to the combination, which contains the smaller number of strips of equal length. Under equal conditions the problem is decided on the basis most favorable to the assortment of products.

Finding of the most favorable combination comes down to solving a system of diophantine equations, such as:

$$A = a_1m + a_2n + a_3p + \delta$$

where:

A =the length of the roll of fabric expressed in cm.
 a =the length of the strip bed expressed in cm.

j, k, l =the numbers of strips acquiring all kinds of values from 1 to i in accordance with the inequality of $j < k < l$

i =the largest number of strips.

m, n, p =the quantity of strips of equal length.

δ =the remnant

2

and then to the selecting of the most favorable solution ensuring the smallest δ (remnant).

The number of equations equals the number of combinations of i multiplied by 3. In order to explain the equations given, the sequence of compiling the equations and their solution should be considered in more detail, as follows:

10 For purposes of selecting the optimum variant of cutting up a roll of fabric it is necessary to compile all the equations and to find all the solutions for each of them, then select the best one.

15 If the cutting is to be performed for three strip beds, then it is described by one equation

$$A = a_1m + a_2n + a_3p + o$$

where a_1, a_2 and a_3 are the lengths of the three strip beds.

20 If, however, the calculation of how to cut a piece of fabric is to be carried out on the basis of four strip beds, actually cutting for not more than three strip beds, then four equations can be compiled, namely,

$$A = a_1m + a_2n + a_3p + o$$

$$A = a_1m + a_2n + a_4p + o$$

$$A = a_1m + a_3n + a_4p + o$$

$$A = a_2m + a_3n + a_4p + o$$

25 It is quite obvious that the number of equations rapidly grows with an increase in the number of strip beds for which the calculations are being made.

30 Each of the equations given above contains four unknowns, namely, m, n, p and o , as a result of which there may exist a large number of alternative solutions, which can be found by the method of trial computations.

35 The above is illustrated with an example, wherein for purposes of clarity simple values will be used, viz., $A=60, a_1=10, a_2=12, a_3=15$.

36 The last equation set forth above can have a multitude of solutions for these values, some of which are given below:

- 40 (1) $m=6, n=p=o=0$
(2) $n=5, m=p=o=0$
(3) $p=4, m=n=o=0$
(4) $m=3, n=0, p=2, o=0$
(5) $m=2, n=2, p=1, o=1$
(6) $m=1, n=4, p=1, o=2$
(7) $m=3, n=1, p=1, o=3$, etc.

45 For selecting the optimum solution, all of the multitude of solutions must be found, and only after this has been done can the optimum one be selected. The roots of the equation, according to the terms of physics, may be expressed only by positive integers.

50 In order to define the most favorable combination, it is necessary to make a great number of computations, which it is not economically expedient to accomplish with the help of ordinary computing machines. Factory calculators usually go through selecting various combinations, relying on their intuition and memory at a small number of counting errors. Needless to say, the combinations selected by them are not always the most favorable.

55 Though efforts have been made to overcome the above mentioned difficulties and shortcomings, no results have been attained, while we have succeeded in solving the problem and in bringing it to a practical realization.

60 It has now been established that the herein claimed machine possesses rapid action ability, ensuring the finding of the most favorable variant for cutting up a roll of fabric within just a few seconds.

Only one machine installed at a large needlework factory can fully satisfy the needs of calculating the cuts.

The purpose of this invention is to create a computing machine capable of finding the most favorable variant cutting up a roll of fabric into strips of prerated length. Another purpose of this invention is to increase the operating efficiency of computers and designers (planners).

This invention also ensures the best method of utilizing fabric by reducing the amount of remnants left over. In connection with the above mentioned purposes this invention is based on a new construction and combining units and elements herein described and claimed for testing. Other advantages of this invention will be disclosed in the description with references to the appended drawings, in which:

FIG. 1 shows the functional diagram of the claimed electronic computing machine.

FIG. 2 shows the diagram for selecting the factor roots. FIG. 3 shows the diagram of composing diophantine equations.

FIG. 4 shows the diagram of entering the numbers of factors.

FIG. 5 shows the diagram of defining the zero remnant value on the summation device (summator).

The described electronic computing machine (see FIG. 1) consists of an input device 1, registers 2 for storage of the initial data (A and a_1-a_7), the summator 3, circuits for defining the zero value of the summator remnant, a programmer consisting of a block 6 of combinations and counter 7 recording the remnant value, a printing (output) device 9 and a control device 10.

The automatic fulfilling of the program put into the machine is ensured by the block of combinations, consecutively forming all the combinations from the lengths of strips and substituting into each equation any possible number of strips. For this purpose the combination block contains a circuit for selecting the roots of factors, a circuit for composing the diophantine equations along three stages of solving these equations, and a circuit for introducing the factor roots into the summator. The counter for registering the remnant values, the content of which upon completing the three stages of solving equations should be increased by one length unit beginning after the zero value, this counter being engaged parallel to the registers of initial data and connected to the summator through the circuit defining the zero value of the factor roots. The summator is connected to the control device through the circuit for defining the zero value of its remnant.

The machine operates in the following way:

On the keyboard of the input device type consecutively he values $a_1, a_2 \dots a_7$ (the length of strips) and value A (the length of the roll of fabric). Through the push-buttons of the register numbers these values are transmitted to the corresponding registers and stored there. By pressing the button 11 "start" on the control device, the synchronizing pulses begin to develop.

By additional code value A is transmitted on the first impulse from the corresponding register to the summator 3 (FIG. 1). The value of the remnant δ is transmitted after that by direct code. Also by direct code after that follows one or the other equation factor transmitted a definite number of times. The order observed here is as follows: first transmitted to the summator "p" number of times comes the third factor, then "n" times the second factor and after that "m" times the first factor up to the moment when the summator shows either zero (which means the end of the solution), or up to the moment of overfilling the summator, when no solution is obtained. In the latter case the signal Σ is received showing overfilling of the summator.

After obtaining the signal Σ the summator is emptied out and the values A are again transmitted into it, as well as value δ and new combination factors.

The cycles of solutions differ as to the value δ transmitted to the summator (in the first cycle $\delta=0$, in the second cycle $\delta=1$ and so on).

The solution stages differ from each other by the quantity of various factors transmitted to the summator (in the first stage the factor roots of the third "p" and the second "n" equal zero; in the second one—"p" equals "0," in the third—combinations of all three factors are transmitted to the summator).

The selection of factor roots at every stage is accomplished by increasing the values from 1 to m, p or n .

The chart of selecting factor roots (FIG. 2) contains: counters 12, 13 and 14 for counting the numbers of factor roots m, n and p respectively; counters 15 and 16 fixing the already used combinations of factor roots and eliminating their further appearance; registers 17 and 18 connected with the outputs of counters 13 and 14 and marking the transition to the next factor root during the process of finding the solution; registers 19 and 20 for recording into the summator the value A—the length of the fabric roll—by reverse code and the rated value of the remnant; circuits of coincidence 21, 22 and 23 controlled by the registers 17 and 18 engaged separately and reswitching the chain of registering the factor roots; coincidence circuits 24, 25 and 26 tied up with the circuits for composing equations and the circuit of registration, which separately engage the chains of rearranging the equations in accordance with the solution stages.

The gates 27 and 28 serve for copying by reverse code the readings on the counters 15 and 16 and transferring them to the counters 12, 13 and 14, the gates operating simultaneously at the moment of transition to a new combination of roots.

The first synchronizing pulse passes through the open gate 29, registers the value A from the respective register to the summator and transfers the register 19 into a unit condition. The second synchronizing pulse passes through the gates 30 and 31, records the value δ from the counter to the summator and changes the register 20 into a unit condition. The gate 31 closes and prepares for opening up the coincidence circuits 21, 22 and 23. The selection of one of these circuits is accomplished through the registers 17 and 18, which in this case open up the circuit 21.

This circuit in its turn opens up the gate 32. The following synchronizing pulses pass through the gates 32 and 33 onto the counter 12 counting their number, and at the same time pass on to the recording circuits (output 34), where they record the first factor on the summator. The gate 33 is open constantly and closes only at the signal Σ showing an overfilled summator.

At the first stage there is a constantly inflowing level signal (input 35), preparing the opening of coincidence circuit 24.

If no solution is obtained, the summator issues a signal of overfilling and the coincidence circuit 24 opens up. To make rearrangement of the equation, the next in turn synchronizing pulse passes through the opened up coincidence circuit 24 for composing equations onto the counter 36 of the first factor number and changes its value. Consequently, the next factor will now take its place in the equation. Before starting the next selection, the counters 12, 13 and 14 of the recording numbers and the registers 17 and 18 will return to zero condition. Then the value A is again entered into the summator followed by the value δ and the next factor.

Every time, when the signal of overfilled summator is received, the synchronizing pulse retained by the delay line 37, accomplishes through the coincidence circuit 38 a transcription by the reverse recording code of counters 15 and 16 of the used up combination fixations to the corresponding counters 12, 13 and 14 for recording numbers.

At the second stage, when the signal indicating an overfilled summator is received together with the second stage signal (input 39) the register 17 is through the coincidence

circuit 40 transferred into a unit condition. Therefore, after recording in the summator the values A and δ , the coincidence circuit 22 will open up first, its outlet pulse opening up the gate 41.

The next in order synchronizing pulse will pass through the gates 41 and 42 to the recording circuit (output 43), where the second factor will be recorded from the respective register to the summator and simultaneously to the counter 13 counting the number of recordings.

Insofar as the counter 13 showed a recording of zero in reverse code, the first pulse will cause its overfilling. This overfilling pulse proceeds to the register 17 and transfers it into zero condition; simultaneously it passes on to the counter 15, where it fixes a unit. The register 17 closes the coincidence circuit 22 and opens up the coincidence circuit 21.

The following synchronizing pulses will pass through the gate 32 to the recording circuit (output 34), where the first factor will be recorded on the summator and also the counter 12 counting the number of these recordings.

If no solution has been obtained, which will be signified by the sign of an overfilled summator, the register 17 is again transferred into a zero condition, a unit in reverse code being transcribed from counter 15 to the counter 13. After recording the values A and δ on the summator, the coincidence circuit 22 opens up. Two pulses for recording the second factor will now be required before the counter 13 becomes overfilled. The root combination will now be different. The pulse from the outlet of counter 13 will change the register 17 into initial condition and will add one unit to the counter 15. Recording of the first factor takes place in the usual way. Consequently, the contents of counter 15 become constantly increased. In the future there may be a situation, at which the overfilling of the summator will be reached even before re-switching the register 17, i.e. as soon as the second factor is recorded. In this case the signal indicating overfilling of the summator will open up the coincidence circuit 25, which is prepared for opening by the constantly incoming second stage signal (input 39) from the equation composing circuit. The synchronizing pulse will pass through the circuit 25 into the equation circuit on counter 44, increasing by one unit the ordinal number of the second factor. The counters of the root pick-up circuits will in this case return to the initial zero condition, the picking of roots proceeding in the usual way.

On the third stage (input at 45), when signals indicating an overfilled summator are received and of the third stage (outputs 39', 45'), the output pulses of coincidence circuits 40 and 46 will transfer the registers 17 and 18 into a unit condition. First to open up after recording the values A and δ in the summator, will be the coincidence circuit 23. This circuit opens up the gate 47 and the next synchronizing pulse passes through the gates 47 and 48 to the recording circuit (output 49), where recording of the third factor will take place. Simultaneously, the pulse will pass on to the counter 14, on which a reverse code zero was already recorded. Therefore, the very first pulse will overfill the counter 14. The signal from the counter output will transfer the register 18 into zero condition, causing the closing of the coincidence circuit 23 and the opening of the coincidence circuit 22.

The next pulse to follow into the summator will be the second one and from there on the work will proceed as in the second stage.

During gradual increasing of the second root, a situation is arrived at, where the signal of overfilling of the summator will appear at the recording of the second factor, i.e. before transferring the register 18. In this case the overfilling signal will open up the coincidence circuit 50 and the synchronizing pulse will pass through it to the counter 16 of used up combinations and will increase its value by one unit. Now two impulses will

already be required before transferring the register 18 after copying the readings from counter 16 to counter 14 in reverse code, i.e. the third factor will already have to be entered twice.

5 The work of the remaining part of the circuit will proceed in a manner similar to that described above.

The gradual increasing of the content of counter 16 will lead to a situation, where the overfilling of the summator will occur as soon as only the third factor is recorded, i.e. before the moment of transferring the register 18. Then the signal of summator overfilling will open up the coincidence circuit 26, this opening being already prepared by the third stage signal constantly incoming from the equation composing circuit (input 45). The next synchronizing pulse will pass through it into the equation composing circuit and on to the counter 51, increasing by one unit the ordinal number of the third factor. In this case the counter of root pick-up return to their initial zero condition. From here on the picking of roots for the new equation will proceed in the same order, as described above.

The circuit for composing diophantine equations consists of: three counters 36, 44 and 51 fixing the numbers of root factors and are connected in parallel to the root pick-up circuit, and four registers 52, 53, 54 and 55, of which two serve to fix the output of the signal of the current stage solution into the circuit of root factor pick-up (to the inputs 35, 39, 45) and the units for the remnant counter (output 56); the other two registers fix the order of root factor selection without repeating the already solved equations and are connected with the outputs of counters 36, 44 and 51, these being interconnected in sequence, in order that the changes in their readings should take place in accordance with the requirements of the solution order, and being also tied up through the copying gates 57 and 58.

The registers 52 and 53 operate in sequence defining the strict order of stages.

In the initial condition of the circuit for counter 36 there is a fixed position corresponding to the first number of the factor, that on the register 44—to the second number of factor, on counter 51—to the third number of factor, while the registers are in zero condition. The pulses for rearranging equations are worked out in the chart of selecting root factors (inputs 59, 60 and 61).

On the first stage the pulse produced in the circuit of selecting root factors follows through the assembly 62 to the input of counter 36, increasing its contents by one unit. In this way, the counter 36 will show the next factor number, i.e. a new equation will be formed. On the first stage of the equation there will be one factor participating, on the second one—two different factors.

In order to distinguish the stages there is the register 53 provided, which switches over the signals of the first or second stages. The counter 36 successively sorts out all the values and is thrown back into initial position, i.e. it tried out all the combinations from the i elements one by one. The signal from the output of this counter appears on the input of the register 53 and transfers it into a unit condition. Then begins the second stage. In order to initially change the numbers of the second factor in the equation, as required by the algorithm, the signals of rearranging equations on the second stage follow through the assembly 63 to the input of counter 44, each time increasing its content by one unit. Thus, the counter 44 will show after every rearranging, the next in order number of the factor. By gradually increasing the readings of counter 44, it will sort out all the values and will be thrown into zero condition, while the signal from its output will proceed to the input of counter 36, increasing its readings by one unit. By this the required order of numerical factor sequence will become disturbed: the numbers of the first factor on the counter 36 will show a larger number than the numbers of the second factor on the counter 44. In order to eliminate this discrepancy

correction is provided in the circuit for composition of equations, which is put into effect by rewriting the readings of counter 36 to counter 44 and by adding to the content of the latter one more unit.

The pulse from the output of counter 44 proceeds to the register 54, transfers it into unit position and thereby opens up the gates 64 and 65. The first synchronizing pulse (which in the recording circuit registers the value in the summator) accomplishes through the gate 65 the rewriting from the counter 36 to the counter 44 in direct code, and then, held up by the delay line 66, passes through the gate 64, adding one unit to the counter 44 and throwing into zero condition the register 54. Thus, before starting the rewriting of this factor, the counter 4 fixes in the summator an ordinal number larger than that on the counter 36 of the first factor, while the register 4 returned into zero position, ensures a one-time rewriting and the addition of a unit.

On the third stage of the equation there already takes part three different factors. To determine the signal indication of the third stage the register 42 is used. As in the foregoing stages, the contents of counter 36 of the first factor number again reaches the maximum value and after the signal of rearranging this counter, is also thrown into initial position. The signal from the output of this counter follows through the open gate 67 to the output 6, through the gate 68 and to the register 52, bringing it into unit condition, thereby displaying the indication of the third stage. In order, first of all, to change in the equation the numbers of the third factor, the signals of rearranging (input 61) of equations follow through the assembly 69 to the input of counter 51, each time increasing its content by one unit. The counter 51 sorts out all values and is thrown into its initial condition, while its output pulse proceeds to the input of counter 44 increasing its readings by one unit. This will cause a disturbance of the required order of sequence of the second and third factors, similar to the one that was described above. In order to maintain the required order there is a correction provided in the circuit, which is effected by re-writing the readings of counter 44 to counter 51 and by adding a unit to the latter.

The gradually increasing readings of counter 44, second factor numbers, will cause disturbance of the sequence order in the numbers of the first and second factors. But on the third stage this disturbance takes place simultaneous with that of the numbers of the second and third factors. For the successive correction of factor numbers the circuit is provided with a dependence allowing to transfer the readings from the counter 44 of the second factor number to the counter 51 of the third factor number only after corrections are made in the numbers of the first and second factors. This function is accomplished by the coincidence circuit 70 allowing the passing of the synchronizing pulses through the gates 71 and 72 and the delay line 73 for correcting the order of numbers of the second and third factors after completing the correcting of number orders of the first and second factors.

The recording circuit (FIG. 4) contains three decoders 74, 75 and 76 connected in parallel with the counters 36, 44 and 51 of the circuits for composing diophantine equations and through the gates 77, 78 and 79 with the summator controlled by this circuit, as well as the assembly 80 and the pulse shaper.

The counters of factor numbers define in the binary code the factor number, which should be recorded for the preset equation. The decoders convert the readings of the counters, i.e. a high level opening up of the gates appears on one of the bus-bars corresponding to the number fixed on the counter. The recording pulses proceed to the gates from the circuit of selecting factor roots of equations (outputs 34, 43 and 45 of the circuit). In order to work out powerful pulses for copying the factors from the reg-

isters of initial data into the summator, there are the pulse shapers 81 with triple-input assemblies 80.

The herein described machine has two circuits for zero analysis. One circuit is designed for defining the zero value of the summator remnant; the other—to define the zero values of factor roots. Since all the factors from input registers of the machine are transmitted to the summator, the signal indication of zero factor is represented by the appearance of zero in the summator. Both circuits are similar in their construction, therefore, only one of them, for instance, the circuit defining the zero value of the summator remnant (FIG. 5), is described here.

The circuit consists of cascade multi-input coincidence charts 81-87. The inputs of the coincidence circuits are connected with the zero outputs of the summator and with those of the input registers. In this way, the high level signal appears on the output 88 of the circuit only, when high potentials characterizing the zero condition of the logical element of every category (for instance, the trigger) appear on the zero output of all categories of the summator.

Although this invention has been described in conformity with the preferred method of realization, it is to be understood, that changes and variations without deviating from the essence and scope of the invention, may take place. Such changes and variations will be considered as not exceeding the scope of this invention when determined by the appended claims.

What we claim is:

1. An electronic computing machine for determining the optimum variant of cutting fabric into strips of a given length, comprising, in combination,

(a) a plurality of memory registers;

(b) means for inputting into said registers data relating to the total length of the fabric to be laid out, and data on the lengths of each of the strips required, with only one kind of data being introduced into each of the registers;

(c) summator means;

(d) means for connecting the outputs of said registers in parallel to the summator means;

(e) programmer means operatively connected to said registers and comprising:

(1) a first plurality of counters for the consecutive selection of combinations from the said registers and the transmission of the data from said registers to said summator means;

(2) a second plurality of counters connected to the input of the first plurality, for setting the factors that characterize the number of times the data of each register is to be introduced into said summator means, whereby the summator sums all the data received from the registers and is capable of producing one of a signal of zero, when the capacity of the summator means coincides with the total sum of the data introduced into it, and a signal of overfilling, when there is no coincidence;

(f) controllers connected to receive said signals of the summator means for terminating the calculations when a zero signal is sent, and for resetting said counters of the programmer means in order to set the next combination of registers to be used in the calculations and the values of the factors applied to the data introduced by the registers;

(g) registering devices connected to both groups of counters of the programmer means for indicating the registers to be used in each cycle of calculations, the data contained in said registers and the factors to be used.

2. An electronic computing machine as claimed in claim 1, in which said first plurality of counters of the programmer means is connected in series, and further comprising means connected between adjacent counters for transfer-

ring the data from each successive counter to the previous counter at the beginning of each cycle of the calculations, whereby new combinations of registers are selected which do not repeat the combinations used in the previous calculation cycle.

3. An electronic computing machine as claimed in claim 1, further comprising means for consecutively changing the capacity of the summator means by an amount equal to a unit of length in each calculation cycle, thereby ensuring a change in the length of remnant tolerated in cutting a piece of fabric.
